(57) CLAIM

The ornamental design for a buckleless comfort belt, as shown and described.

DESCRIPTION

FIG. 1 is a front perspective view of a buckleless comfort belt, showing my new design;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The buckleless comfort belt is shown with a symbolic break in its length. The appearance of any portion of the buckleless comfort belt between the break lines forms no part of the claimed design. The broken dash-dot lines in the figures show portions of the buckleless comfort belt which form no part of the claimed design. The evenly-broken dash-dot lines in the figures represent stitching which form no part of the claimed design.
